UNITED STATES PATENT OFFICE

HENRY A. MINER, OF EVANSTON, ILLINOIS, ASSIGNOR TO W. H. MINER, INC., OF CHICAGO, ILLINOIS, A CORPORATION OF DELAWARE

DOOR OPERATING MECHANISM

Application filed November 17, 1930. Serial No. 496,157.

This invention relates to improvements in door operating mechanisms.

One object of the invention is to provide a simple and efficient operating mechanism for refrigerator car doors, which is accommodated well within the clearance limits imposed and whereby forcible opening movement of the doors is assured to an extent to entirely free the doors from sticking and thus 10 permit the operator to easily swing the same completely open.

Another object of the invention is to provide a door operating mechanism for forcing refrigerator car doors tightly closed and also 15 forcing the same partly open, including keepers mounted on the door frame and cooperating keeper-engaging means operated by a rotary shaft mounted on one of the door members, actuated by a lever, wherein the keeper- 20 engaging means has camming action with the keeper to impart an amount of movement to the doors in opening the same which is in excess of the movement imparted thereto in the closing operation, thereby assuring complete 25 freeing of the doors so that there will be no resistance due to sticking of the same in the final manual operation of directly swinging the same to fully opened condition.

A more specific object of the invention is 30 to provide a door operating mechanism for forcing the doors of a refrigerator car partly open and also operative to forcibly close the same, including a vertically disposed, rotary lever operated shaft mounted on one of the doors and having keeper-engaging means at 35 opposite ends thereof, and cooperating keepers mounted on the door frame wherein each keeper-engaging means is of fork shape and one of the branches of the forked keeper-engaging 40 means co-acts with a projecting lug-like member of the cooperating keeper when the shaft is rotated in one direction to force the doors closed, and wherein when the shaft is rotated in a reverse direction the two 45 branches of the forked keeper-engaging means have engagement successively, respectively, with an abutment face of the cooperating keeper and the lug thereof, to force the doors open, thereby obtaining greater 50 movement of the door during the opening

operation than during the closing operation thereof, to assure complete freeing of the door so that the same may be easily manipulated by the operator to complete the opening thereof.

Other objects of the invention will more clearly appear from the description and claims hereinafter following.

In the drawings, forming a part of this specification, Figure 1 is a front, elevational view of a pair of vertically disposed hinge doors of a refrigerator car, illustrating my improvements in connection therewith. Figure 2 is a horizontal sectional view, on an enlarged scale, corresponding substantially to the line 2—2 of Figure 1, said view also showing the keeper engaging means of my improved construction in a different position in dotted lines. Figure 3 is a partly diagrammatic view, similar to Figure 2, illustrating in dotted lines two different positions of the keeper-engaging means and the actuating shaft.

In said drawings, 10 designates the side wall of a refrigerator car having a door opening 11 therein, with which two hinge doors 12 and 13 cooperate. As clearly shown in Figure 1, the doors 12 and 13 are mounted to swing about vertical axes and are supported by hinge members 14—14 fixed to the door frame. As shown, preferably two such hinge members are employed in connection with each door. As will be understood, the meeting edges of the doors and the door frame, as well as the inner meeting edges of the two doors, are beveled and provided with suitable packing material, as is usual, to provide for a tight joint when the doors are fully closed.

My improved door operating mechanism comprises broadly a rotary operating shaft 90 A; a pair of keepers B—B; a pair of fork-shaped keeper-engaging members C—C fixed to the operating shaft; an operating lever D; and a pair of supporting brackets F—F.

The operating shaft A is in the form of a substantially flat bar arranged vertically of the door 12, adjacent the inner edge thereof. At opposite ends of the bar A, keeper-engaging members C—C are fixed. Each keeper-

engaging member C has a slotted stem 15 receiving the corresponding end of the bar A, the stem being fixed to the bar by any suitable means such as rivets extending therethrough. 5 Outwardly of the stem 15, each member is of cylindrical form, as indicated at 16, thereby providing a journal portion, which is rotatably supported in the corresponding bracket F fixed to the door 12. Outwardly beyond the 10 bracket F, the keeper-engaging member C is provided with a keeper-engaging means proper in the form of a crescent-shaped, horizontally disposed web member 17, having a vertically disposed arcuate flange 18, projecting 15 therefrom. As clearly shown in Figures 2 and 3, the flange 18 is of uniform cross section throughout and is in the form of a fork element. In other words, the flange 18 is of arcuate form or crescent-shape. 20 The operating shaft A has a lever D pivoted thereto by means of a pin 19, the lever D being swingable from the horizontal position shown in Figure 1 to a pendant position. As shown, the lever D is provided with a 25 hand grip by which the same may be oscillated to rotate the shaft A in reverse directions. A sealing and latching means 20 of well known form cooperates with the lever D, by means of which the lever may be locked in 30 the position shown in Figure 1, and the usual car seal applied thereto. The member 20 is preferably mounted on the door 13.

The keepers B—B are of similar design, except as hereinafter pointed out. One of 35 the keepers B is secured to the door frame adjacent the upper edge of the door 12, and the other keeper is secured to the frame adjacent the lower edge of said door. Each keeper B is in the form of a casting and has 40 an inclined inner abutment face 21, which co-acts with the corresponding keeper-engaging member during the initial portion of the door opening operation. Spaced outwardly from the face 21, the keeper has a laterally 45 extending lug 22, which has an inclined inner abutment face 23 and an outer abutment face 24 substantially parallel to the plane of the car wall. The keeper B at the bottom edge 50 of the door opening is provided with an extension 25 having a pivoted latch member 26 at the outer end thereof which cooperates with the lower edge of the door 13 to latch the same in closed position. As shown, the 55 lower end corner of the door 13 is provided with a wear plate 27 with which the latch 26 cooperates.

The operation of my improved mechanism is as follows: Assuming that the doors 12 and 13 are closed, and the door operating 60 mechanism is in the full line position shown in Figures 1 and 2, the latch 26 is first disengaged from the door 13 and the opening operation is effected by rotating the operating shaft A by means of the lever D, the latter being 65 swung from the position shown in Figure 1

outwardly and toward the door 12, thus rotating the operating shaft in a counter-clockwise direction, as viewed in Figure 2. As the shaft A is thus rotated, the outer surface of the crescent-shaped flange 18 will be brought into engagement with the cam face 21, as clearly shown at 28 in Figure 3. As the shaft A is further rotated, the crescent-shaped flanges 18 of the keeper-engaging members will assume the position indicated by 29 in Figure 3, wherein the outer face of the inner branch of the crescent-shaped or forked member is still engaged with the cam face 21 of the keeper and the extremity of the other branch is contacting with the outer face 24 of the lug 22. During this action, the door 13 will be pulled outwardly also, due to the frictional contact with the door 12. As will be clear, when the operating parts have reached the dotted line position last referred to in connection with Figure 3, the door 12 will have been forced partly open. During the further rotation of the shaft A, the outer arm of the crescent-shaped keeper-engaging flange will cam on the face 24 of the lug 22 until the parts assume the dotted line position shown in Figure 2, which represents the extreme opening movement of the door 12 as produced by the operating mechanism. When the parts have reached this position, the door 12 will be entirely free from the door 13 and the door frame, thus permitting the operator to swing the same to fully open condition without interference. When the door 12 has been opened, the door 13 is swung open in the usual manner. In closing the doors, the door 13 is first swung shut and latched by the member 26. The door 12 is then moved to partly closed position so that the crescent-shaped keeper engaging flanges of the operating means will cooperate with the projecting lugs 22—22 of the keepers B—B. As will be evident, when the shaft A is rotated in a clock-wise direction by means of the lever D, as viewed in Figure 2, the crescent or forked-shaped keeper-engaging members will engage over the projecting lugs 22—22 of the keepers B—B, the branch at the lefthand side of the keeper, as shown in dotted lines in Figure 2, engaging the inner inclined face 23 of the corresponding lug, thereby camming the door inwardly. When the door has been fully closed, the parts assume the full line position shown in Figure 2.

As will be evident, my improved door operating mechanism provides for a greater movement of the door 12 in opening than in closing of the same. This additional movement is effected through the fork shaped members cooperating with the spaced abutment faces of the keepers successively, thereby assuring freeing of the door 12 and preventing all sticking due to accumulation of 130

frost on the engaging edges of the doors and the door frame.

I have herein shown and described what I now consider the preferred manner of carrying out my invention, but the same is merely illustrative and I contemplate all changes and modifications that come within the scope of the claims appended hereto.

I claim:

- 10 1. In a door operating mechanism, the combination with a member having a door opening and a swinging door; of a pair of keepers fixed to said door member adjacent the edges of the door, each of said keepers having spaced inner and outer abutment faces; an operating shaft rotatably supported on the door; means for rotating said shaft; keeper-engaging means fixed to opposite ends of said shaft, said keeper-engaging means being of fork shape, the arms of said fork members successively engaging respectively said abutment faces of the keepers to force the door open when said shaft is rotated in one direction.
- 25 2. In a door operating mechanism, the combination with a member having a door opening and a swinging door for closing said opening; of a keeper fixed to the door member adjacent one edge of the door, said keeper having an abutment face and a lug spaced outwardly from said face; a rotary operating shaft on said door; means for rotating said shaft in reverse directions; a fork shaped keeper-engaged member fixed to one end of said shaft and rotatable therewith, said fork member engaging with said lug of the keeper when the shaft is rotated in one direction to force the door closed, and the arms of said fork shaped member successively engaging said abutment face and lug of the keeper respectively when said shaft is rotated in a reverse direction to force the door open.
- 35 3. In a door operating mechanism, the combination with a member having a door opening, and a door for closing said opening; of a keeper fixed to the door member adjacent one edge of the door, said keeper having an inner abutment face and a laterally projecting lug spaced from said face; a rotary shaft on said door; means for rotating said shaft in reverse directions; a keeper-engaging member fixed to one end of said shaft, said keeper-engaging member including branch elements connected at their inner ends and extending outwardly from a point coincident with the axis of rotation of said shaft, said branches respectively and successively engaging the abutment faces and lug of said keeper, and having camming engagement therewith to force the door open.
- 40 4. In a door operating mechanism for refrigerator car doors, the combination with a member having a door opening therein; of a swinging door for closing said opening;
- 45 of a pair of keepers fixed to said member above and below the door, said keepers each having spaced abutment faces; a vertically disposed rotary operating shaft mounted on said door; and fork shaped keeper-engaging means at opposite ends of said shaft and rotatable therewith, the branches of each of said forked keepers being successively engageable with the abutment faces of the corresponding keeper to force said door open upon rotation of said shaft in one direction.
- 50 5. In a door operating mechanism, the combination with a door frame; of a pair of doors hinged to said frame; a pair of keepers fixed to the door frame above and below said doors, each of said keepers having a laterally extending lug and an abutment face inwardly of the lug; a vertically disposed rotary operating shaft mounted on one of said doors; crescent shaped keeper-engaging means at opposite ends of said shaft and rigid therewith, each of said crescent shaped keeper-engaging members successively engaging said abutment face and lug of the corresponding keeper when the operating shaft is rotated in one direction, thereby forcing the door open, said crescent shaped keeper-engaging members engaging with said lug when the shaft is rotated in a reverse direction to force the door closed.
- 55 6. In a door operating mechanism, the combination with a door frame; of a pair of doors hinged to said frame; a pair of keepers fixed to the door frame above and below said doors, each of said keepers having a laterally extending lug and an abutment face inwardly of the lug; a vertically disposed rotary operating shaft mounted on one of said doors; arcuate flange-like, keeper-engaging members fixed to the opposite ends of said shaft, the arcuate flange of each of said keeper-engaging members exteriorly engaging said abutment face and interiorly engaging said lug, when the shaft is rotated in one direction, to force said door open, and engaging over said lug and having camming action thereon when said shaft is rotated in a reverse direction to force said doors closed.
- 60 In witness that I claim the foregoing I have hereunto subscribed my name this 13th day of November, 1930.
